UNITED STATES PATENT OFFICE.

MARIE HAFELY AND ALFRED C. HAFELY, OF NEW YORK, N. Y., ASSIGNEES
TO KOCH, SONS & COMPANY, OF SAME PLACE.

DESIGN FOR A BOOK OR ALBUM.

SPECIFICATION forming part of Design No. 19,487, dated December 17, 1889.

Application filed September 18, 1889. Serial No. 324,358. Term of patent 7 years.

To all whom it may concern:

Be it known that we, MARIE HAFELY, a citizen of Switzerland, and ALFRED C. HAFELY, a citizen of the United States, both residing in the city and State of New York, have invented and produced a new and original Design for a Book or Album, of which the following is a specification, reference being had to the accompanying drawings, in which—

- 10 Figure 1 represents two album-leaves as in an open album, and Fig. 2 is a sectional view. The leading feature of this design consists of a book or album the outline or configuration of the leaves of which is that of an acute-
15 angle tetragon. The back edge *a* and front edge *b* are parallel to each other, or nearly so. The top edge *c* is oblique, so that the angle between the top edge *c* and front edge *b* is acute, and the bottom edge *e* is at an obtuse

angle to the front edge *b* and preferably 20 slightly rounding at 3. The corner 4 is preferably clipped or rounding.

The design of the shape and configuration of the openings *g* *h* for the pictures form no necessary part of this design, as the same may 25 be omitted or varied without changing the leading feature of our design.

What we claim is—

In a design for a book, the design of the leaves, substantially herein shown and de- 30 scribed.

Signed by us this 13th day of September, 1889.

MARIE HAFELY.
ALFRED C. HAFELY.
